CLAIM

The ornamental design for an edible pet chew, substantially as shown and described.

DESCRIPTION

FIG. 1 is a perspective view of the edible pet chew, showing our new design;

FIG. 2 is a left side elevational view thereof;

FIG. 3 is a right side elevational view thereof;

FIG. 4 is a top plan view thereof;

FIG. 5 is a bottom plan view of FIG. 4;

FIG. 6 is a rear elevational view thereof; and,

FIG. 7 is a front elevational view thereof.

The bold line illustrated circumferentially showing along the outer surfaces of the claimed design separates regions of different contrasts.
